MICROMINIATURE RELAY FOR TRANSISTOR CIRCUITS

Carl N. Challacombe and Roger A. Rieckman, Elgin, Ill., assignors to the United States of America as represented by the Secretary of the Army

Filed Dec. 19, 1961, Ser. No. 160,676
4 Claims. (Cl. 200—97)

The present invention relates to hermetically sealed microminiature relays in the sensitivity range of 500 microwatts to 1.0 milliwatt for use in transistor circuits.

The function of relays in many applications is the control of a comparatively large amount of power with a small amount of power. When the power available to operate the relay becomes very small (on the order of a milliwatt or less) it is not sufficient to operate relay contacts in a conventional manner.

Recourse has been made in these low operating power situations to sensitive polarized relays and meter movement relays to accomplish the switching operations. However, polarized and meter type relays are undesirable for various reasons. Polarized relays require a volume of four to five times that required by the relay of the instant invention. In addition, the polarized aspect was unwanted. The major drawbacks of meter type relays are the lack of current handling ability in the contacts, the large size due to the magnet volume needed, and poor shock and vibration resistance. When the above mentioned relays are used, sacrifices must be made in size, ruggedness, and versatility to achieve the goal of controlling a large amount of power with a small amount of power.

Where only a low operating power is available for actuating the relay contacts, the current carrying ability of the contacts is limited, especially in the conventional button or blade type contacts. Considerable pressure on the contacts is essential to handle the amount of power for which the relay of this invention was designed. Because the relay operating power is insufficient to operate the contacts in a conventional manner, a mechanical source of energy is supplied within the relay of this invention in the form of a mainspring. The release of this energy is controlled through an escapement which may be operated at very low levels of power. The stored energy is used to operate the contacts which switch higher levels of power.

An object of this invention is to provide a relay which will switch powers on the order of 20 to 30 watts with relay operating powers of 1 to 5 milliwatts while retaining the size, shock and vibration resistance, and non-polarized aspects of certain "crystal can" size relays.

Another object of this invention is to provide a new and novel relay.

Still another object is to provide a novel relay having shock and vibration resistance.

A further object of this invention is to provide a relay which occupies a relatively small volume and yet is capable of switching comparatively high currents.

A still further object of this invention is to provide a relay which utilizes a mechanical source of energy to operate the relay contacts.

The specific nature of the invention as well as other objects and advantages thereof will clearly appear from the following description and drawings wherein:

FIGURE 1 is a front view of the relay,

FIGURE 2 is a side view of the relay,

FIGURE 3 is a detailed view of the escapement mechanism of the relay,

FIGURE 4 is a detailed view of the actuator mechanism and contacts, and

2

FIGURE 5 is a detailed view which shows the various connections which are made to the lead out terminals.

Referring to FIGURES 1 and 2, there is shown a microminiature relay which is hermetically sealed within an outer can 38. Can 38 is omitted from FIGURE 2 in order to simplify the drawings. An inner can 37 separates the coil structure from the remainder of the relay. In order to obtain the desired length of coil and yet keep the overall size of the relay small, it is necessary to use two coils 73 and 74. The core is made of four pieces. A U-shaped piece 5 is inserted through the coils from the top and pieces 6 and 7 are inserted from the opposite ends of coils 73 and 74, respectively. The core pieces overlap throughout the length of the coils thus providing a long, large area, gap inside the coils. A better condition is thus achieved than could be obtained by a joint outside the coil. This type of core construction allows the inner can 37 to be soldered to a center plate 40 and to the cores 6 and 7 where they leave the can. The fourth core piece 8 is secured to core piece 7 by core screws 24. Two insulating hermetic seals 71 are placed in plate 40 inside the area covered by can 37 to support coil terminals 32. Two conductive leads 70 connect coils 73 and 74 to the ends of terminals 32 which extend inside can 37. A conductive lead 61 connects coils 73 and 74 in series. Coils 73 and 74 are wound upon insulating coil tubes 10, while an insulating coil form end 9 is positioned at the end of each coil. A core rivet 22 secures a tab on core member 5 to center plate 40.

The energy needed to operate the two common relay contacts 48 is stored in the form of a wound spring (not shown) which is located within a barrel and cover 2. The barrel, housing the mainspring, revolves about an arbor 3 which is secured to the center plate 40. The mainspring is attached to the arbor and the barrel.

Rotation of the barrel due to the wound mainspring is coupled through an amplifying gear train to an escapement. When the electromagnetic circuit is energized the escapement is unlocked and energy is available to operate the contacts.

The first gear 72 of the train is actually an integral part of the barrel 2 and it drives a pinion 31 which is mounted on a staff 30. A gear 13 which is also mounted on staff 30 drives a pinion 29 causing gear 12 to drive pinion 28 which in turn causes gear 11 to drive pinion 27. Gears 12 and 11 are fixedly mounted on shafts with pinions 29 and 28 respectively.

The escapement mechanism can be more clearly seen in FIGURE 3. The escapement wheel 35 is mounted on a shaft along with pinion 27 so that it turns in the direction shown along with pinion 27. The armature 1, which is mounted on a staff 26, has two sapphire escapement pins 18 and 18a mounted thereon which are adapted to engage the escapement wheel teeth. Pin 18 is generally referred to as the locking pin and 18a the holding pin. In FIGURE 1 the armature 1 is shown in the non-energized condition of the relay, while in FIGURE 3 the relay is in its energized condition. Armature stop 55, mounted on a post 20a, keeps the armature in proximity to core piece 8 when the relay is not energized. As the relay becomes deenergized the armature return spring 50, which is mounted on a post 51, returns the armature to the position shown in FIGURE 1. A stop 25, mounted on a post 20a, keeps the armature in proximity to core piece 8 when the relay is not energized. As the relay becomes deenergized the armature return spring 50, which is mounted on a post 51, returns the armature to the position shown in FIGURE 1. A stop 23 limits the travel of the return spring. The gap length between armature 1 and core piece 6 varies when the armature pivots, being greatest when the armature is in the released position while the coils are deenergized. To prevent, as much as possible, any increase in the total of the armature gaps in the magnetic circuit, a sandwich-type gap arrangement is used between armature 1 and core piece 8 to improve flux transfer at this point.

To improve vibration resistance of the relay the angle on the face of the escapement wheel teeth is such that the escapement wheel must back up or reverse-rotate 5 against the mainspring torque as the locking pin 18 is withdrawn.

The actuator and switching mechanism is best seen in FIGURE 4 while the switch itself is shown in FIGURE 5. The actuator wheel 36 is mounted on the same shaft as escapement wheel 35 and is provided with an undulating rim 60. The actuator arm 44 is mounted to 10 the actuator shaft 43 which is a sapphire rod. Two sapphire rods 46, which are attached to arm 44, ride on either side of rim 60 to provide a cam follower action that actuates the common switch contacts 48. With this type of cam and follower the actuator arm is restrained in all positions. Four fixed contacts 47 and the two common contacts form a double-pole, double-throw of switch. A flexible conducting lead 42 connects each of the common contacts 48 to header terminals 65 and 67. Each of the fixed contacts 47 is connected to a respective 20 header terminal 62, 63, 68, or 69. The remaining header terminals 64 and 66 are connected to coil terminals 32 by two conductive leads 75. Header terminals 62 to 69 project through an insulating header 14.

Two supporting plates 39 and 41 are secured to header 25 14, while the center plate 40 is secured to the supporting plates by spacing posts 20, 20a, and 21. Jewels 15, 16, 17, and 49, mounted in the various plates, provide bearings for the gear, armature, and actuator shafts or staffs.

The operation of the relay is as follows:

The escapement wheel tends to rotate in the direction shown by the arrow in FIGURE 3 since it is coupled to the mainspring through the gear train. The armature is normally in the position shown in FIGURE 1 due to the action of the return spring, and therefore locking pin 18 prevents rotation of the escapement wheel. When the electromagnetic circuit of the relay is energized, the armature is rotated one half tooth space to the position shown in FIGURE 3, and holding pin 18a prevents rotation of the escapement wheel. A rotation of one 35 half tooth space occurs again as the electromagnetic circuit is de-energized. As the escapement wheel rotates, the actuator wheel also rotates since the two are on the same shaft. Movement of the undulating rim of the actuator wheel causes the actuator arm to move as the two rods 46 follow the undulations of rim 60. Since the common contacts 48 of the double-pole, double-throw switch are connected to the actuator shaft 43, the reciprocating movement of the actuator arm is imparted thereto. Thus as the electromagnetic circuit is energized, the common contacts are switched to one set of fixed contacts 47, and as the electromagnetic circuit is de-energized, the common contacts are switched back to the other set of fixed contacts.

By this construction and manner of operation a relay of very small size is achieved, yet it is rugged and reliable, and is capable of controlling relatively large currents with low input power. It is capable of many thousands of cycles of operation, tested models having achieved upward of 250,000 switching operations per winding.

What we claim is:

1. In an electromagnetic relay having a pair of contacts for controlling an external circuit, a source of stored energy, an escapement wheel having a plurality of teeth

4 around the periphery thereof, said escapement wheel being coupled to said energy source, an electromagnet positioned adjacent said escapement wheel and having a flat U-shaped core having two arms joined by a cross-piece and a movable armature, said armature being pivoted in overlappnig relation and closely adjacent to one of the arms of said core so that the gap formed thereby is small and relatively fixed at all times, the armature and the remaining core arm forming a working gap, said armature being provided with a locking pin which engages one of said teeth when said electromagnet is de-energized, and a holding pin which engages one of said teeth when said electromagnet is energized, means connected to said locking pin for returning said armature back to its initial position when said electromagnet is de-energized, and actuator means connected to said escapement wheel for operating said contacts by the energy released through said escapement wheel.

2. A relay as set forth in claim 1 wherein the faces of each escapement wheel tooth form an angle with a line extending from the center of the wheel to said face such that said wheel must reverse-rotate when said electromagnet is energized, thereby giving resistance to vibration to said relay.

3. A relay as set forth in claim 1 wherein said actuator means includes an actuator wheel having an undulated rim, said actuator wheel being mounted on a shaft with said escapement wheel so that both wheels rotate together; an actuator arm having two follower rods mounted thereon, one of said rods being situated on each side of said rim; said contacts being connected to said arm.

4. An electromagnetic relay comprising: a mainspring, an escapement wheel having a plurality of teeth around the periphery thereof, a gear train coupling said mainspring to said escapement wheel, an actuator wheel having an undulated rim, a shaft, said escapement wheel and said actuator wheel being fixedly mounted upon said shaft, an actuator arm having two follower rods mounted thereon, one of said rods being situated on each side of said rim, a switch having a movable contact, said movable contact being connected to said actuator arm, an electromagnet having a U-shaped core comprising two arms joined by a cross-piece, a coil situated on each arm of the core, an armature pivotably mounted adjacent the arms of the core so that one portion thereof is brought into contact with one of the core arms when said electromagnet is energized, a return spring for returning said armature to an initial position when said electromagnet is de-energized, said armature being provided with a locking pin which engages one of said teeth of said escapement wheel when said electromagnet is de-energized, and a holding pin which engages one of said escapement wheel teeth when said electromagnet is energized, said switch being operated when said electromagnet is energized and 55 being reset for repeated operation when said electromagnet is de-energized.
